UNITED STATES PATENT OFFICE.

CYRUS EVERSON, OF COMMERCE, MISSOURI.

IMPROVED SCREW-DRIVER.

Specification forming part of Letters Patent No. 57,107, dated August 14, 1866.

To all whom it may concern:

Be it known that I, CYRUS EVERSON, of Commerce, Scott county, State of Missouri, have invented a new and useful Improvement in Screw-Drivers; and I do hereby declare that the following is a full, clear, and exact description thereof, which will enable others skilled in the art to make and use the same, reference being had to the accompanying drawings, forming part of this specification, in which—

Figure 1 is a side view of my improved screw-driver, partly in section, to show the construction of the handle. Fig. 2 is a bottom or edge view of my improved screw-driver. Fig. 3 is an end or head view of my improved screw. Fig. 4 is a cross-section of my improved screw-driver, taken through the line *x x*, Fig. 1.

Similar letters of reference indicate like parts.

My invention has for its object to furnish an improved screw-driver, so constructed and arranged as to be strong, serviceable, and convenient, and free from any liability to split the head of the screw in operating it; and it consists, first, in forming the face or edge of the screw-driver in the form of a cross with equal arms, so as to fit into the head of the screw; and, secondly, in combining with the handle of the screw-driver a ratchet-wheel and pawls, as hereinafter more fully described.

A is the screw, which is made in the usual form, except that the head is formed with two notches crossing each other at right angles, as shown in Fig. 3. When formed in this way the notches in the head of the screw do not require to be so deep to enable the driver to take a firm hold upon the head of the screw to operate it as is necessary when the head of the screw is formed in the ordinary manner.

B is the shank or blade of the screw-driver, the edge or face of which is made in the form of a cross with equal arms, as shown in Fig. 2, so as to fit into the double notch in the head of the screw.

The shank or blade *B* of the screw-driver is made detachable from the handle *C*, as shown in Fig. 1, and is held in place in the socket of the handle in the same manner as bits are now ordinarily held in the socket of the brace.

To the upper end of the hub *c'* of the handle *C* is attached a shank, *c²*, running longitudinally through the handle, as shown in Fig. 1, and terminating in a nut or button, as shown. This shank *c²*, or at least that part of it that passes through the ratchet-wheel, must be square, so that the hub *c'* cannot turn without carrying the said ratchet-wheel with it.

The ratchet-wheel *D* works in a case, *c³*, attached to the end of the wooden handle *c⁴*, and which has one of its sides projecting for the reception of the double pawl *E*. The teeth of the ratchet-wheel *D* and the two ends of the pawl *E* are so formed that the wheel may be held by the pawl from turning in either direction, as desired. The pawl *E* is pivoted to the projecting part of the case *c³*, as shown in Figs. 1 and 4.

In using the screw-driver to drive a screw, the forefinger of the hand that holds the screw-driver is placed upon the proper end of the pawl, and the screw may be forced in its whole length without shifting the hand. To draw out the screw the finger is shifted to the other end of the pawl and the screw drawn out with the same facility.

I claim as new and desire to secure by Letters Patent—

1. Forming the face or edge of the screw-driver *B* in the form of a cross with equal arms, substantially as described, and for the purpose set forth.

2. The combination, with the handle *C* of the screw-driver, of a ratchet-wheel, *D*, and pawl *E*, constructed and operated substantially as described, and for the purpose set forth.

CYRUS EVERSON.
